(57) **CLAIM**

The ornamental design for a color, haze and clarity measurement instrument, as shown and described.

DESCRIPTION

FIG. 1 is a perspective view of a color, haze and clarity measurement instrument, with a chamber lid closed, showing my new design;

FIG. 2 is a front elevation view thereof;

FIG. 3 is a rear elevation view thereof;

FIG. 4 is a side view thereof;

FIG. 5 is an opposite side view thereof;

FIG. 6 is a top view thereof;

FIG. 7 is a bottom view thereof; and,

FIG. 8 is an alternative, perspective view thereof, with the chamber lid opened.

The broken lines applied to the color, haze and clarity measurement instrument, which may appear in any of FIGS. 1-8, represent unclaimed subject matter. All broken lines are for environmental purposes only and form no part of the claimed design. The shade lines show surface contour and not surface ornamentation.
